DISPENSING DEVICE

Filed April 26, 1932

UNITED STATES PATENT OFFICE

EGBERT ALEXANDER, OF LOS ANGELES, CALIFORNIA

DISPENSING DEVICE

Application filed April 26, 1932. Serial No. 607,553.

This invention relates to improvements in dispensers and more particularly to that type used for delivering sugar or other granular substances and especially designed for table use:

It is an object of this invention to construct a dispensing attachment which may be readily attached to containers now on the market and which may be manually manipulated to repeatedly deliver measured quantities of granular material from the container as desired.

Another object of the invention is to provide a simplified device of the character stated wherein the measuring recess is so constructed and arranged that the side wall of the container forms a portion of the wall of said recess thereby lessening the amount of material which it is necessary to use in manufacturing the attachment.

Still another object of the invention is to simplify the construction of devices of this character, this being done in part by shaping a plate of sheet metal in such a manner that a portion of said plate assists in walling in the measuring compartment and another portion of the same plate forms a bearing for the shaft or pivot pin whereon the dispensing element rocks.

Other objects, advantages and features of the invention may hereinafter appear.

Referring to the accompanying drawing which illustrates what is at present deemed to be a preferred embodiment of the invention,

Fig. 1 is a vertical mid-section of an embodiment of the invention wherein the container consists of a glass jar having screw threads formed around its open end, the dispensing attachment consisting of sheet metal having a peripheral flange which is provided with corrugations thus forming threads for screwing upon a threaded portion of the container.

Fig. 2 is a transverse section looking up from the line 2—2 of Fig. 1.

Fig. 3 is a top plan view of the structure shown in Fig. 1.

Fig. 4 is a top plan view like that of Fig. 3 except that only the central portion of the

device is shown, the exterior portion being broken away to contract the view and parts being shown in a different operative position from that of Fig. 3.

Fig. 5 is a fragmental transverse section on line 5—5 of Fig. 1.

Fig. 6 is a fragmental transverse section of another form of the invention on a plane corresponding to that of Fig. 5.

Fig. 7 is a vertical section on line 7—7 of Fig. 6.

Referring in detail to the drawing, the container 1 is provided with a corrugated open end portion 1a upon which is screwed a sheet metal cap member 2 having a laterally extending peripheral flange 2a which is corrugated in order to provide threads for screwing the attachment on to the open end of the container in the position shown.

It will be seen that a spring 22 is positioned in tension between the underside of the cap 2 and member 6 to hold the rotor 10 in a closed position to close chamber 3 from outside of member 1 when not in use.

The measuring recess 3 is located between the plate 2a which forms the body portion of the cap 2 and a rockable plate 6 is arranged in parallel spaced relation to the plate 2a. Said recess 3 is of a triangular character and in one form is completed on its outer side by the adjacent wall of the corrugated portion 1a of the container, the other two vertical sides of said recess being formed by the wings 7 of a plate which is formed from an elongated rectangular blank, the middle portion of which is bent into a substantially cylindrical form to produce a sleeve 8 which forms a bearing for the shaft or pivot pin 9 about which the operative parts of the device rock.

The means shown for manually operating the dispensing element include a top or outer disc 10 which is soldered or otherwise secured to the outer end of the shaft 9 and which is provided near its periphery with a tail piece or finger hold 11 engageable by a finger or the thumb for the purpose of rocking said disc 10. Said disc 10 is provided with a peripheral notch 14 which is adapted by the manually operable means which has been de-

scribed to be brought into and out of register with a substantially triangular opening 15 with which the cover plate 2a is provided near its periphery.

5 Referring again to the inner plate 6 which forms the inside wall of the dispensing recess 3, said plate 6 is rigidly secured to the lower end of the shaft 9 and is so positioned with relation to the outer disc 10 that whenever any portion of the notch 14 of said disc is in register with the opening 15, said plate 6 will completely close the lower side of said recess 3; but when said notch is moved completely out of register with said opening 15, 10 a farther movement of the measuring device in the same direction will cause the plate 6 to move out of register with the lower side of said recess. In order to regulate the extent of the rocking movement of the dispensing device, the plate 6 is provided with two stop ears 17 and 18 which are so positioned as to limit properly the rocking movement of the manually operable elements.

20 In the form of the invention shown in Figs. 2 to 5, the wings 7 of the bent plate already referred to are connected at their outer ends by an arcuate plate 20 which completes the side walls of the measuring recess 3; but in the form of the invention shown in Figs. 6 and 7 the outer portion of the wall of the recess is formed by the adjacent wall of the container 1. In both of these forms the plate having the wings 7 is so bent as to provide the bearing sleeve 8, but in Figs. 6 and 7 the bent plate is provided with a neck portion 21 which unites said sleeve 8 with the wings 7.

25 In both forms of the invention the rockable measuring member comprises two plates which are spaced apart from each other, each 40 of said plates being cut away to provide a feed, the cut away portion of one of said plates being circumferentially spaced away from the cut away portion of the other plate in order to prevent the granular material from flowing from the container in a continuous stream at any time.

30 Owing to the general similarity of construction between the two forms of the invention, the parts in Figs. 6 and 7 are lettered the same as the corresponding parts in the other views, the additional reference character 21 being applied to the neck or extension which is supplied in the form shown in Figs. 6 and 7 in order that the measuring recess be extended out to the periphery of the container and yet remain relatively small in capacity.

35 In the form of the invention shown in Figs. 6 and 7, the measuring recess has its outer wall formed by the wall of the container, and therefore it is possible to form the other two side walls of the measuring recess out of a single strip of metal which is bent in such a manner that the central portion of the strip forms a bearing and there is at each end of

the strip a limb which forms a side wall of the measuring recess. The side walls of the measuring recess can be formed by less die work in the form of the invention shown in Figs. 6 and 7 than in the alternative construction. 70

I claim:

1. A dispensing device of the kind described comprising, in combination, a container, a cap member secured to said container and forming a closure therefor, said cap member having a dispensing opening, and a manually operable dispensing element rockably mounted upon said cap member to repeatedly dispense measured quantities of material from said container through said opening in the cap, said cap member having a bent plate provided with wings which form two of the side walls of the dispensing recess, the middle portion of said bent plate forming a bearing for the pivot of the manually movable parts. 80

2. In a dispensing device, in combination, a container, a rockable measuring member comprising two plates spaced apart from each other, each of said plates being cut away to provide a feed, the cut away portions of said plate being circumferentially spaced apart, and a combined bearing member and measuring recess member consisting of an elongated plate bent at its central portion to form a bearing sleeve, the end portions of said plate forming the side walls of the measuring recess, said rockable measuring member comprising a shaft which has its bearing within said sleeve. 90

3. In a dispensing device, in combination, a container, a rockable measuring member comprising two plates spaced apart from each other, each of said plates being cut away to provide a feed, the cut away portions of said plate being circumferentially spaced apart, and a combined bearing member and measuring recess member consisting of an elongated plate bent at its central portion to form a bearing sleeve, the end portions of said plate forming the side walls of the measuring recess, said rockable measuring member comprising a shaft which has its bearing within said sleeve, one of the plates of said rockable member having laterally directed portions which form stops engageable with said bent plate to limit the extent of the rocking movement of said measuring member. 105

4. In a dispensing device, in combination, a container, a rockable measuring member comprising an outer and an inner plate, said plates being spaced apart from each other to provide room for a measuring recess between them, each of said plates being cut away to provide a feed, the cut in the inner plate consisting of a recess opening out at the edge thereof, a measuring recess member consisting of a bent strip having spaced limbs 115 120 125 130

cated between said plates and forming the inner portion of the side wall of the measuring recess, the outer portion of the wall of the measuring recess being formed by a portion of the wall of the container, and means to manually rock said measuring member to feed material in measured quantities from said container through the cut away portions of said plates.

10 5. In a dispensing device, in combination, a container, a rockable measuring member comprising an outer and an inner plate, said plates being spaced apart from each other to provide room for a measuring recess between them, each of said plates being cut away to provide a feed, a measuring recess member consisting of a bent strip having a central portion shaped to form a bearing and having end portions spaced apart from each other thereby producing limbs which form side walls of the measuring recess, the outer portion of the wall of the measuring recess being formed by a portion of the wall of the container, a pivot member in fixed relation to the container with which the bearing portion of said bent strip cooperates, and means to manually move said measuring member to feed material in measured quantities from said container through the cut-away portions 30 of said plates.

6. In a dispensing device, in combination, a container having a cap, a plate mounted within the container and supported by said cap in spaced relation thereto to provide a measuring recess between said cap and plate, said cap and plate each having cut-away portions adjacent to the periphery of said container, said cut-away portions being circumferentially spaced apart, a pivot member supported by said cap, a measuring recess member consisting of a strip bent upon itself in such a manner that its end portions form spaced apart limbs to provide side walls for the measuring recess, the periphery of the container forming the outer wall of said measuring recess and the central portion of said strip being bent to form a bearing which cooperates with said pivot member, said strip having between said bearing and its spaced 50 apart limbs a neck portion wherein the two runs of the strip are secured to each other, and means to rock said measuring member to deliver measured quantities of material from the container.

55 In testimony whereof, I hereunto affix my signature.

EGBERT ALEXANDER.
